UNITED STATES PATENT OFFICE

MEANS FOR FORMING TUBES FROM TUBULAR BLANKS

Walter A. Curtis, Cleveland, Bishop & Babcock, Cleveland, Ohio, a co-
Application May 18,
4 Claims.

Application May 18, 1945, Serial No. 594,562

180-89

This invention relates to the working of tubular blanks, and has to do with a process of reducing the wall thickness of tubular metal blanks with corresponding elongation thereof while shaping the resultant tube to desired inside and outside diameter, and to means for practicing the process.

It is known to reduce the wall thickness of tubular metal blanks and to thereby form a blank into an elongated tube, by drawing operations performed by appropriate dies. Such dies are expensive and subject to rather rapid wear rendering them unsuitable for continued use. In many cases any considerable reduction in the wall thickness of the blank requires the use of a multiplicity of dies and annealing of the blank after each drawing operation, which is expensive and time consuming.

My invention is directed to a process and means whereby the wall thickness of a tubular metal blank may be substantially reduced, with corresponding elongation of the blank, in a single operation and without the use of expensive dies or other parts subject to excessive wear. In performing the process of my invention, the tubular blank, mounted on an interior mandrel, is subjected to radial and axial pressures by forming means, with relative movement between such means and the blank lengthwise of the latter, whereby the metal of the wall of the blank is displaced to desired depth and is redistributed lengthwise of the blank so as to cause elongation thereof. More specifically, the mandrel with the blank mounted thereon is advanced through a coaxial forming assembly comprising a plurality of rotatably mounted forming members defining with the blank a forming passage having an annular exit portion of a radius greater than that of the mandrel by the desired wall thickness of the tube to be produced, and a substantially conical entrance portion of greater diameter at its entrance end than the outside diameter of the blank, leading to and converging toward the exit portion. The assembly is rotated at appropriate speed and upon relative movement between the assembly and the blank lengthwise of the latter, the forming members apply axial and radial forming pressures to the wall of the blank, with the area of application of such pressures advancing along the blank, whereby the wall thereof is reduced in thickness to the desired extent and proportionately elongated as above stated. The rotatably mounted forming members preferably are in the form of rollers each having an end portion tapered toward the mandrel and a

2.5% of the total number of patients in the study had a history of smoking.

cylindrical body portion, though within the broader concept of my invention any other analogous forming members may be used. Further objects and advantages of my invention will appear from the detail description.

In the drawings:

Figure 1 is a semi-diagrammatic sectional view, with certain parts shown in elevation, of means for performing the process of my invention, illustrating the first step of such process:

Figure 2 is a view similar to Figure 1 but illustrating the displacement and redistribution of

trating the displacement and redistribution of the metal of the wall of the blank with resultant thinning of the wall and elongation thereof;

Figure 3 is a side view, partly in section, of the assembly for applying rolling forming pressure to the wall of the blank; it consists of

enlarged scale taken substantially on line 5-5 of Figure 4 but showing a blank on the mandrel with the wall of the blank thinned for a portion of its length by the axial and radial pressures applied thereto by the rotatably mounted forming members of the assembly.

In Figures 1 and 2 of the drawings I have indicated a chuck 10 of the head stock of a lathe, this chuck being of conventional type and requiring no detailed description. Chuck 10 is

aligned with chuck 11, or similar holding means, of the tail stock of the lathe. A cylindrical mandrel 12 is mounted at one end in member or chuck 11 and extends therefrom in coaxial relation to a forming assembly 13 secured in chuck 10. The assembly 13 comprises a race 14 having secured to its back face a ring 15 of a width to extend a substantial distance radially inward beyond race 14, the latter having at its forward face a plurality of forwardly extending bosses 18 spaced equidistant circumferentially thereof. A front ring 17 is secured conveniently by shoulder

front ring 17 is secured, conveniently by shouldered screws 18 to the forward ends of bosses 16, by which it is spaced from race 14. It will be seen that the race 14 and the front ring 17 define between them slots 19, defined as to length by the bosses 16, opening outward radially of the assembly 13. A cage 20 is disposed within the assembly 13 in concentric relation thereto, this cage being provided with a plurality of circumferentially spaced slots 21 which receive rollers 22, the slots 21 being somewhat less in width than the diameter of the respective rollers 22, as will

be understood. Each of the rollers 22 comprises a cylindrical body portion 22^a and a tapered portion 22^b of substantially frusto-conical shape and tapering toward the mandrel 12. The diameter of cage 20 is such as to hold the rollers 22 in contact with race 14, at the inner circumferential face thereof, with the cage 20 centered in the assembly 13. It will be seen that the back retaining ring 15 extends radially inward beyond race 14 sufficiently to provide an abutment or stop for the outer ends of the rollers 22, which are flat at their outer ends as shown, and the front retainer ring 17 extends radially inward beyond race 14 a sufficient distance to provide a stop for the flat inner ends of the rollers. In that connection, the rollers fit fairly snugly between the retainer rings 15 and 17, but not tightly, and the cage 20 fits fairly snugly about the body portions of the rollers but also not tightly. The rollers 22 have a slight amount of looseness or play to accommodate themselves to the surfaces being acted upon, but without excessive tilting of the rollers such as would tend to cause them to bite into the wall of the blank being operated upon. From the above description of the assembly 13, it will be apparent that the rollers 22, when produced, as during rotation of the assembly 13, define between them a space or opening having a cylindrical exit portion and a substantially conical entrance portion extending to and converging toward the cylindrical exit portion.

In Figure 1 I have shown a cup shaped metal blank 24, produced in a known manner, closed at one end by an end wall 25 pierced at 26, this blank being mounted upon the end portion of mandrel 12 adjacent the assembly 13. The mandrel 12 is of substantially the same diameter as the inside diameter of blank 24 and fits snugly therein, so to support the circumferential wall of the blank against inward radial displacement. The tapered inner end portions 22^b of the rollers 22 of assembly 13 define a substantially conical entrance portion, as above noted, of a diameter at its entrance end greater than the outside diameter of the blank 24, and the body portions 22^a of the rollers 22 define a substantially cylindrical exit portion, of the space or passage above referred to, of a radius greater than the radius of the mandrel 12 by an amount equal to the desired wall thickness of the tube to be formed from the blank.

After the blank 24 has been mounted upon mandrel 12 in proper relation to the assembly 13, as above described, the chuck 11, and with it the mandrel 12 and blank 24, is moved toward the assembly 13 so as to introduce the blank 24 into assembly 13 in coaxial relation thereto and thereafter move it lengthwise through the assembly. During movement of the blank 24 into and through the assembly 13, the assembly is rotated at appropriate speed. Introduction of the blank 24 and the mandrel 12 into the assembly 13 brings the circumferential wall of the blank into pressure contact with the forming members or rollers 22, which are then caused to rotate about their own axes while also rotating with the assembly 13 about its axis of rotation. In the continued travel of the blank 24 through the assembly 13, the tapered end portions 22^b of the rollers 22 exert considerable pressure on the wall of the blank, this pressure in part being directed lengthwise or axially of the blank toward the other end thereof, there also being a larger component of radial pressure applied by

the tapered portions 22^b of the rollers to the wall of the blank. In that manner the metal of the wall of the blank is displaced to a depth determined by the difference between the radius of mandrel 12 and the radius of the cylindrical passage or space defined between body portions 22^a of the rollers 22. As the metal is displaced from the wall of the blank it is redistributed towards the other end thereof by the tapered end portions of the rollers, and the thinned area of the wall of the blank is rolled down and smoothed by the cylindrical body portions of the rollers, and shaped to substantially uniform wall thickness about the mandrel 12. During the operation of reducing the thickness of the wall of the blank the rollers 22 provide, in effect, with the mandrel 12, a forming passage having an annular exit portion and an entrance portion leading to and tapering toward the exit portion, so that when the blank is advanced by the mandrel through the assembly 13 in pressure contact with the forming members or rollers 22, the metal of the wall of the blank is displaced and redistributed in the manner above stated. In the continued advance of the blank through the assembly, the displaced metal of the wall of the blank is continuously shifted or displaced toward the opposite or open end of the blank, the net result being that as the wall of the blank is reduced in thickness it is proportionately elongated.

It will be seen that the rollers 22 have small area of contact with the wall of the blank, such contact being restricted to substantially line contact. It will also be clear that since the forward or inner ends of the rollers 22 are of substantially conical or tapered formation, the peripheral speed of the tapered end portion of each roller increases outward or toward the body portion of the roller, and the metal of the wall of the blank is displaced in very small increments. I consider that of importance in that desired flow of metal along the wall of the blank lengthwise thereof is readily initiated, after which the metal may readily be displaced from the wall of the blank and kept flowing continuously therewith. In that connection, the travel of the rollers about the wall of the blank in pressure contact therewith, in the continued rotation of the assembly 13, heats by friction and pressure the metal of the blank wall so as to render it more flowable than would otherwise be possible without this heating effect, which also contributes to ready displacement and flow of the metal of the wall of the blank in the manner stated. It will be appreciated that some force is required to advance the mandrel 12 and the blank 24 mounted thereon through the rotating assembly 13 and that the forming members or rollers 22 are subjected to outward radial thrusts. The race 14 is of adequate mechanical strength to take such thrusts and, since the rollers are rotated above their respective axes during the forming operation, neither this race nor the rollers are subjected to objectionable wear. Also, during travel of the mandrel and the blank through the assembly 13, the rollers are subjected to axial thrust, which is taken up by the blank retainer ring 15, seated in the chuck 10 of the lathe, the parts being of adequate mechanical strength for that purpose.

The taper of the inner portion 22^b of the respective rollers 22 influences the rate at which the metal of the wall of the blank may be displaced and redistributed without risk of crack-

ing or tearing of the thinned area of such wall. This taper appears to have a definite relation to the shear strength and the compression strength of the metal being operated upon. In working deep-drawing brass, for example, such as 80-20 brass, comprising eighty percent copper and twenty percent zinc, the taper of the inner end portions 22^b of the respective rollers 22 should be such that the included angle between this end of the roller and the circumferential wall of the blank 24 is within the range of from about thirty-three degrees to twenty-seven degrees, depending upon the degree of hardness of the brass. I have found that an angle of approximately thirty degrees gives the proper proportion between the shear strength and the compression strength of 80-20 deep drawing brass of any degree of hardness, whereby the maximum advantage of both is attained.

Since the tapered ends 22^b of the rollers 22 have substantially line contact only with the wall of the blank, the thinned area of such wall need not be subjected to substantial lengthwise tension by the mandrel 12 in order to effect rapid displacement and redistribution of the metal of the blank in the manner above stated. That is of importance in avoiding subjecting the thinned area of the blank wall to stresses such as would be apt to cause rupture or tearing thereof, and renders possible very substantial reduction in thickness of the wall of a tubular blank in a single continuous operation. I have reduced the wall of a tubular brass blank, formed of 80-20 brass, from a thickness of .04" to .025" in a single continuous operation, and it is possible by properly relating the rollers 22 to the mandrel 12, and driving the forming assembly 13 at appropriate speed, to reduce the wall of the blank to a much greater extent.

Referring more particularly to Figure 5, as the blank 24 is advanced through the assembly 13, the metal displaced from the wall of the blank by the tapered inner end portions of 22^b of the rollers 22 may, in certain cases, tend to pile up in advance of the rollers somewhat in the manner indicated at 30, it being understood that this piling up of the displaced metal is exaggerated for purposes of illustration. In certain cases the displaced metal might tend to accumulate to such an extent as to interfere objectionably with the continuous operation of the process. It is possible, when that occurs, to back out the mandrel with the partially reformed blank and remove the bur or rib of displaced metal by cutting or filing it away, or in any other suitable manner, and to then reinser the mandrel and the blank into the assembly 13 and continue the operation. In order to avoid such temporary interruption of the operation, however, I preferably provide means whereby objectionable burs or excessive displaced metal may be removed by the operation of the rotating assembly 13, whereby the wall of the blank may be reduced in thickness to the desired extent and correspondingly elongated in a single continuous operation. To that end, the cage 20 is formed in lengthwise section as shown in Figure 5, having its forward portion 20^a reduced in thickness or radial extent and of rectangular cross section, the main or body portion of the cage 20 also being of substantially rectangular cross section, and the cage as a whole being made of suitably hardened steel. The forming of the cage 20 in the manner stated provides a sharp edged point or cutting element 20^b at the forward ends of the respective roller re-

ceiving slots in cage 20, at each side of the slot and adjacent the forward ends of the rollers. These cutting elements 20^b function to trim off any objectionable excess of displaced metal, and the resultant chips are discharged radially through the slots 19, previously referred to, by centrifugal force incidental to rotation of the assembly 13. In that connection, I contemplate flushing the area of the blank being operated upon and the assembly 13 with a suitable lubricating solution, which assists in the radial discharge of metal chips through the slots 19, so as to guard against any metal particles entering between the body portions of the rollers 22 and the area of the wall of the blank being operated on thereby. That is of importance since entrance of metal particles between the body portions of the rollers and the wall of the blank would render the thinned area of such wall objectionably rough and, in addition, might cause cracking or rupturing of the thinned blank wall. It will be seen that by my invention I render it possible to reduce substantially the wall thickness of a tubular blank, as indicated in Figures 2 and 5, and to elongate correspondingly the wall of the blank so as to produce an elongated relatively thinned walled tube, in a single continuous operation. I accomplish this result by means of comparatively simple construction not subject to excessive wear in use and which is much less expensive than the die equipment which would be required for effecting a considerable reduction in wall thickness of a tubular blank by known drawing operations.

While in the above description of my invention I have referred to moving the mandrel 12 and the blank 24 mounted thereon through the assembly 13 while rotating the latter, it will be understood that the relative movements of the parts may be reversed, that is, the mandrel 12 and the blank 24 mounted thereon may remain stationary as to axial movement thereof and the assembly 13 may be moved lengthwise of the blank while being rotated thereabout. Further, instead of rotating the assembly 13, the mandrel 12 with the blank 24 mounted thereon may be rotated while the assembly 13 remains stationary with respect to rotation. Obviously axial movement may be imparted to both the assembly 13 and the mandrel 12 and the blank 24 mounted thereon, and either the assembly 13 or the mandrel 12 with the blank 24 mounted thereon, or both, may be rotated. In other words, my invention comprehends, in its broader aspects, imparting relative movement to the blank and the forming assembly axially thereof while also imparting relative rotation to the blank and the forming assembly, with the forming members or rollers in pressure contact with the circumferential wall of the blank, regardless of which particular member or members of the apparatus are rotated or moved axially. As above indicated, and as will be understood by those familiar with the metal working art, changes in details of my invention, with respect to both the process and the means for practicing it, may be resorted to without departing from the field and scope of my invention, and I intend to include all such variations, as fall within the scope of the appended claims, in this application in which the preferred form only of my invention has been disclosed.

I claim:

1. In a roller assembly, a race member of substantial radial and axial extent having an inner

cylindrical surface, a ring secured to the outer end of said race member projecting radially inward thereof, a ring secured to the inner end of said race member projecting radially inward thereof, a cage disposed in substantially concentric spaced relation to said inner surface of said race member and to said rings, said cage having therein axially extending circumferentially spaced slots, and a plurality of rollers respectively mounted in said slots between said rings restrained thereby against axial movement relative to said race member, each of said rollers comprising a cylindrical body portion having at its inner end an inwardly tapering element, the body portions of said rollers seating against said inner surface of said race member and defining a substantially cylindrical exit portion of said assembly, said tapered elements defining a substantially conical entrance portion of said assembly converging toward and leading to said exit portion.

2. In a roller assembly, a race member of substantial radial and axial extent having an inner cylindrical surface, a cage disposed in substantially concentric spaced relation to said inner surface of said race member, a plurality of rollers mounted in said cage for free independent rotation, and means restraining said rollers against axial movement relative to said race member, each of said rollers comprising a cylindrical body portion having at its inner end an inwardly tapering element, the body portions of said rollers seating against said inner surface of said race member and defining a substantially cylindrical exit portion of said assembly, said tapered elements defining a substantially conical entrance portion of said assembly converging toward and leading to said exit portion, said cage being provided adjacent the inner ends of said rollers with spaced cutting elements extending radially inward thereof.

3. In a roller assembly, a race and a plurality of circularly caged rollers rotatably mounted therein, each comprising a cylindrical body portion having at its inner end an inwardly tapering

5 element, the body portions of said rollers having bearing contact with the inner face of said race and defining a substantially cylindrical exit portion of said assembly and said tapered elements defining a substantially conical entrance portion of said assembly converging toward and leading to said exit portion, and means providing spaced cutting elements extending radially inward of said assembly adjacent the inner ends of said rollers.

10 4. In a roller assembly, a unitary race and a plurality of circularly caged rollers rotatably mounted therein, each comprising a cylindrical body portion having at its inner end an inwardly tapering element, the body portions of said rollers having bearing contact with the inner face of said race and defining a substantially cylindrical exit portion of said assembly and said tapered elements defining a substantially conical entrance portion of said assembly converging toward and leading to said exit portion, said assembly having outwardly opening radial slots in the zone of said tapered elements of said rollers, and means providing spaced cutting elements extending radially inward of said assembly adjacent the inner ends of said rollers.
